AIR OR GAS COMPRESSOR

William Frederick Jennings, Worthing, England

Application October 14, 1936, Serial No. 105,606
In Great Britain October 16, 1935

4 Claims. (Cl. 230—183)

This invention relates to improvements in air or gas compressors and has for its object improved means for transferring the compressed air or gas from the first or low pressure cylinders to the second or high pressure cylinders from whence the compressed air or gas is discharged with means for cooling the air or gas so transferred, the arrangements generally tending to increased efficiency, and silent running of the machine at high speed.

With the usual method of operating two-stage compressors at the present time it is essential to employ in each pair of low and high pressure cylinders at least four valves, two suction valves and two delivery valves, either of the spring urged ring valve or poppet valve type, which are always a potential source of trouble and necessitate a considerable amount of clearance in both the low and high pressure cylinders thereby decreasing the volumetric efficiency of the compressor.

To overcome these disadvantages, in the present invention, three of the four valves referred to above are eliminated by the employment of a single reciprocating sleeve valve with ports to control the air or gas inlet to the low pressure cylinder and the discharge of the partially compressed air or gas from the low pressure cylinder, either direct or through an intercooler, into the high pressure cylinder, through a series of ports in the cylinder wall, which are uncovered by the flat top high pressure piston at the bottom of its stroke, then further compressed to its final pressure by the flat top high pressure piston on the upstroke and discharged through the automatic spring controlled delivery valve situated in the cylinder cover.

The intercooler aforesaid may be a separate entity of any well known type disposed outside the machine or as in one specific construction embodying the invention, hereinafter described and illustrated by way of example, the partially compressed air or gas may be cooled during transfer by passage through a coil immersed in the cylinder jacket water.

An air or gas compressor according to the present invention therefore comprises a pair of superimposed cylinders with superimposed trunk pistons, the low pressure cylinder being fitted with a single reciprocating sleeve valve having inlet and outlet ports and the high pressure cylinder with inlet ports in the cylinder walls and an automatic delivery valve in the cylinder cover.

The invention is applicable to two-stage air or gas compressors of either the single or multi-

cylinder type. When embodied in a two stage air or gas compressor of the multicylinder type, as in the example hereinafter described and illustrated, comprising pairs of superimposed low and high pressure cylinders disposed side by side, the sleeve valves, in association with the low pressure cylinders, control the air or gas inlets to the low pressure cylinders and the discharge of the partially compressed air or gas from the low pressure cylinder of one pair of cylinders to the high pressure cylinder of the other pair and from the low pressure cylinder of the latter pair to the high pressure cylinder of the first pair of cylinders through inlet ports in the lower ends of the high pressure cylinders which are uncovered by the high pressure pistons at the bottom of their strokes, the partially compressed air or gas which in the course of its passage from the low to the high pressure cylinders passes through coils immersed in the water of the cylinder jackets, being further compressed in the high pressure cylinders to its final pressure by the high pressure pistons on their up strokes and discharged through the automatic delivery valves in the cylinder covers.

The invention also includes a modification of the two stage compressor, whereby it may operate as a three-stage compressor, with the working capacity not limited to the volume of the low pressure cylinder or cylinders but increased to the full volume of both the low and high pressure cylinders.

But in order that the invention may be more clearly understood reference may now be made to the accompanying drawing illustrating by way of example a sectional elevation, partly broken away, of an air or gas compressor of the multi-cylinder type with the improvements applied thereto.

Referring to the drawing it will be seen that in the example illustrated the compressor body comprises two main cylinders formed by the outer walls *a* and *b* and the common intermediate wall *c* and liners *d* and *e* are inserted in these two cylinders, the lower parts of which with their liners provide the low pressure cylinders *f* and *g*. The high pressure cylinders *h* and *i* above the low pressure cylinders *f* and *g* are formed in dependences from a heavy cover *k* by which a joint is made with the main cylinders and the liners *d*, *e*. The low pressure pistons *l* and *m* carry extensions on their upper surfaces which serve as the high pressure pistons *n* and *o*.

The sleeves valves *p* and *q* are inserted between the low pressure pistons *l* and *m* and the

low pressure cylinders *f* and *g* and are reciprocated in the usual manner by means of eccentrics from the crank shaft, the cranks of which associated with the pistons *l* and *m* are arranged in opposite directions so that when the pistons *l* and *n* are at the bottom end of their stroke the pistons *m* and *o* are at the top of their stroke.

The main air or gas inlet ports *r r'* in the liners *d* and *e* are in communication with the annuli *s* in the cylinder walls *a b c*, that communicate with the atmosphere, and co-act with the inlet ports *t t'* of the sleeve valves *p* and *q*.

The outlet ports *u u'* in the sleeve valves *p* and *q* are adapted to register with the cut away edges *v v'* of the shoulders formed by the setting back of the liners *d* and *e*, and thereby lead to the lower annuli *w w'* formed between the liners *d e* and the walls of the high pressure cylinders *h* and *i*.

Inlet ports *x x'* lead to the high pressure cylinders *h* and *i* from the similarly formed upper annuli *y y'*.

The lower annulus *w* on the one side is in communication with the upper annulus *y'* on the other side of the machine by means of the pipe coil *z* (shown in dash-dot lines on the drawing) disposed in and passing through the water jacket 2 and similarly the lower annulus *w'* on this latter side communicates with the upper annulus *y* above and on the same side as the annulus *w* by means of the pipe coil *z'* (shown in full lines on the drawing) that also passes through the water jacket 2.

The delivery valves one of which is shown at 3 are contained in false safety heads 5 and 6 resting on the tops of the high pressure cylinders *h* and *i*. Water passages 7 in the cover *k* are in communication with the jacket 2 by which means a similar cooling of the compressed air is obtained as is effected by the coils *z z'* disposed in the main jacket 2.

On the upstroke of the low pressure piston *l* with the high pressure piston *n* the low pressure air or gas expelled through the ports *u* and past the cut-away edges *v* into the annulus *w* passes by the passage 8 into the coil *z* which delivers the air or gas into the annulus *y'* by way of the passage 9. From the annulus *y'* the cooled low pressure air or gas enters the high pressure cylinder *i* by way of the ports *x'* when the piston *o* is at the bottom of its stroke and is compressed and discharged through the delivery valve in the false safety head 6 on the upstroke of the piston *o*.

A similar series of operations takes place with respect to the transfer of the low pressure air or gas from the low pressure cylinder *g*, and it will be clear that the partially compressed air or gas from the low pressure cylinder of the one pair of cylinders is passed in a cooled condition to the high pressure cylinder of the other pair for compression and delivery and from the low pressure cylinder of the latter pair to the high pressure cylinder of the first pair for compression and delivery and with the combination of the sleeve valve controlling the inlet and discharge as described and the arrangement of the false safety head carrying the delivery valves and the jacketed high and low pressure cylinders a small clearance, very efficient and silent machine running at high speed is obtained.

In order to act as a three stage compressor the two stage construction hereinbefore described may be modified by fitting additional suction or inlet valves to the top of either the high pressure cylinder or cylinders, or high pressure piston or

pistons, or both, through which air or gas compressed in the crank case by the down stroke of the piston or pistons, is supplied prior to the opening of the ports *x* to admit air or gas compressed in the low pressure cylinder or cylinders. Thus compressed air or gas is admitted to the high pressure cylinder or cylinders during the whole of the down stroke of the piston or pistons. The crank case must of course be provided with suction or inlet valves, which must be constructed with each line of motion work separately enclosed.

A compressor modified as described above for three stage compression operates in the following manner:

Air or gas at atmospheric or low pressure is sucked through the suction or inlet valves into the crank case by the up stroke of the piston or pistons. During the subsequent down stroke of the piston or pistons, the air or gas is compressed in the crank case up to a predetermined relatively low pressure A, when it is forced or passes through the suction or inlet valves into the top of the high pressure cylinder or cylinders. Towards the bottom of the piston stroke the air or gas which has been compressed to an intermediate pressure B, in the low pressure cylinder or cylinders, enters the high pressure cylinder or cylinders through the ports *x* in the lower parts of the walls thereof, which have then become uncovered by the high pressure piston or pistons, and compresses the air or gas admitted to the cylinder or cylinders from the crank case at pressure A to its own pressure B without any mechanical aid. The upstroke of the high pressure piston or pistons then compresses the air or gas from pressure B to the final pressure C at which it is discharged through the delivery valve or valves in the head of the high pressure cylinder or cylinders.

What I claim is:

1. A two-stage air or gas compressor comprising a plurality of units each including superimposed high and low pressure cylinders and superimposed high and low pressure pistons in trunk form in said cylinders, an inlet chamber common to and communicating with the low pressure cylinders, an independent inlet chamber for each of the high pressure cylinders, an outlet chamber for each low pressure cylinder, conduits connecting the outlet chamber of the low pressure cylinder of one unit with the inlet chamber of the high pressure cylinder of the other unit, and a sleeve valve for each unit comprising a tubular element arranged between the low pressure pistons and the low pressure cylinders and formed with a series of openings to be associated with the inlet ports of the cylinders in a predetermined position of the element and an upper series of ports at all times in registry with the outlets of the cylinders, said element operating to control communication between the common inlet chamber and the low pressure cylinder and also serving to control communication between the outlet of each low pressure cylinder of one unit with the inlet of the high pressure cylinder of the other unit.

2. A construction as defined in claim 1, where in the outlet chamber of the low pressure cylinder of each unit is formed to afford more extended communication between the low pressure cylinder and the outlet of that cylinder than between the low pressure cylinder and the inlet of that cylinder in the operation of the sleeve valve.

3. A construction as defined in claim 1, including water jackets for the cylinders, the conduits between the outlet of the low pressure cylinder of one unit and the inlet of the high pressure cylinder of the other unit passing through the water jackets.

4. A construction as defined in claim 1, including a pressure controlled outlet valve for each of the high pressure cylinders, said valves being aligned with and directly responsive to the high pressure pistons.

WILLIAM FREDERICK JENNINGS.
